UNITED STATES PATENT OFFICE.

JOHN F. O'CONNOR, OF CHICAGO, ILLINOIS, ASSIGNOR TO WILLIAM H. MINER, OF CHAZY, NEW YORK.

FRICITION SPRING-GEAR.

1,226,579.

Specification of Letters Patent. Patented May 15, 1917.

Application filed October 18, 1915. Serial No. 56,428.

To all whom it may concern:
Be it known that I, JOHN F. O'CONNOR, a citizen of the United States, residing at Chicago, in the county of Cook and State of Illinois, have invented a certain new and useful Improvement in Friction Spring Gears, of which the following is a full, clear, concise, and exact description, reference being had to the accompanying drawings, forming a part of this specification.

This invention relates to improvements in friction spring gears.

The object of this invention is to provide a laminated spring gear of high capacity, long stroke, and adapted for standard draw-bar pockets and sill spacing.

In the drawing forming a part of this specification, Figure 1 is a longitudinal, vertical sectional view of a draft rigging showing my improvements in connection therewith. Fig. 2 is a longitudinal, horizontal sectional view on the line 2—2 of Fig. 1. Fig. 3 is a transverse, vertical sectional view taken substantially on the line 3—3 of Fig. 2. Figs. 4 and 5 are detail perspectives of the wedge and one of the followers employed in the structure illustrated in Figs. 1, 2 and 3. Figs. 6, 7, 8, 9 and 10 are views corresponding respectively with Figs. 1, 2, 3, 4 and 5, but illustrating a different embodiment of my improvement, Fig. 7 being taken on the line 7—7 of Fig. 6 and Fig. 8 on the line 8—8 of Fig. 6.

In said drawing, and referring first to Figs. 1 to 5, inclusive, 10—10 denote the center sills having rear stops 11 and front stops 12 secured thereto. The draw-bar 13 is shown as operatively connected with the gear hereinafter described, by a yoke 14 and coupler key 15 and the gear is supported by means of a saddle plate 216 bolted to the lower flanges of the sills 10. The improved gear proper consists of two similar followers A—A, four sets of laminated springs B—B and a wedge C. More specifically described, each follower A has a vertical outer end face 16, upper and lower parallel walls 17 and 18 and two angularly disposed pockets 19—19 within each of which a set of springs B is received. Each of the spring pockets 19 has upper and lower flat walls 20—20, parallel inclined side walls 21—21 and a rear inclined, concave, vertically extending wall 22. As clearly appears from Figs. 2 and 5, the pockets 19 open toward

the center of the gear and thereby permit the insertion of the sets of springs B—B. Each set of springs B consists of a plurality of substantially rectangular spring plates 23—23 all of the same size and shape, and 60 in normal position, flat, as shown in Fig. 2. The opposed faces of the four sets of springs B—B form, roughly, the outlines of a diamond and are arranged in pairs at angles to each other. The wedge C, as 65 shown, is provided with four, vertically extending wedge faces 24—24, each of said wedge faces 24 coöperating with a spring B. The wedge C is also preferably cored to lighten the same and to reduce cost. A 70 retaining bolt 25 extends through each of the followers A—A and also through the wedge C and thus hold the parts in assembled relation. As shown in Fig. 2, the inner vertical faces 26—26 of the followers A—A 75 are spaced apart a distance corresponding to the total movement of the gear, and when said followers come into engagement with each other under either buff or draft the action of the gear is thereby limited, as will 80 be understood.

In operation, upon either buff or draft, the followers A—A approach each other relatively, thereby causing the four sets of springs B—B to be flexed outwardly or 85 away from the center line of the gear, the springs flexing against the concave faces 22—22. Also, there is a friction action which takes place between the faces of the wedge C and the end plates 23 of the sets of springs B—B so that a very high capacity 90 is obtained both in direct spring action and also in friction action. The arrangement is simple, cheap, and the spring plates 23 may all be of the same size and form. It 95 is apparent that the capacity may be regulated as desired by varying the number of spring plates or their thickness or both.

Referring now to the structure illustrated in Figs. 6 to 10, the arrangement of sills, stops, draw-bar, coupler key, yoke and tie plate are substantially the same as those shown in the preceding figures. Each of the followers A'—A' is provided with an outer vertical end face 116 adapted to engage with the stops, and a pocket or recess 19 which opens toward the center of the gear. Each of said pockets or recesses 19 is preferably formed by upper and lower, parallel flat walls 120—120 and curved side 110

walls 122—122. A floating wedge C' is employed and two sets of springs B'—B'. As clearly shown in Fig. 7, each set of springs B' consists of a plurality of spring plates 123 which are normally flexed as shown. Each spring set B' approximates a semi-elliptic spring presenting an outer convex face 40 adapted to coöperate with two of the curved walls 122 of the followers and an inner, concave face 41 adapted to coöperate with the convex faces 124 of the wedge C'. The height of the wedge C' is so proportioned that it slides between and is guided by the upper and lower walls 120—120 of the two followers. Also, the followers are so arranged as to limit the action of the gear in the same manner as previously described for the structure illustrated in Figs. 1 to 5.

Upon either buff or draft, the followers 20 A'—A' approach each other thereby causing the sets of springs B'—B' to be flexed between the wedge C' and the curved walls 122—122 and, as will be understood, friction is created between the plate springs 123 due 25 to their sliding or slipping upon each other during the flexing action.

I claim:

1. In a draft rigging, the combination with followers, and a centrally located, 30 wedge block, of plate springs supported between said followers and adapted to be flexed between said followers and said block upon relative approach of said followers, said wedge being longitudinally movable 35 relatively to both followers upon relative approach of the latter.

2. In a draft rigging, the combination with followers, and a centrally located, longitudinally movable wedge block, of 40 plate springs supported between said followers and adapted to be flexed between said followers and said block upon relative approach of said followers, the block being movable relatively to the followers during

said relative approach, said followers being provided with curved surfaces against which the springs are adapted to be flexed. 45

3. In a draft rigging, the combination with followers, and a centrally located wedge block, said wedge block being tapered toward each end thereof with the longest dimension of a cross section extending parallel to the axis of the gear, of sets of plate springs supported by said followers, said springs being adapted to be flexed between said followers and said block upon relative approach of the followers. 55

4. In a draft rigging, the combination with followers, and a centrally located wedge block, said wedge block being tapered toward each end thereof with the longest dimension of a cross section extending parallel to the axis of the gear, of sets of plate springs supported by said followers, said springs being adapted to be flexed between said followers and said block upon relative approach of the followers, each of said followers having two opposed curved surfaces, inclined to the axis of the gear and against which said plate springs are adapted 60 to be flexed. 70

5. In a draft rigging, the combination with a pair of followers, each having a pair of curved surfaces, one on each side of a vertical plane passing through the center 75 line of the gear, of a centrally located wedge supported by said followers, and sets of plate springs interposed between said followers and said wedge, said springs being flexed against said curved surfaces upon 80 relative approach of the followers, the action of the gear being limited by engagement of the followers with each other. 85

In witness that I claim the foregoing I have hereunto subscribed my name this 7th day of October, 1915.

JOHN F. O'CONNOR.
